DESIGN FOR A DUST COVER FOR VOICE RECORDING MACHINES

Charles C. Walker, Winfield, Iowa

Application March 9, 1945, Serial No. 118,381

Term of patent 14 years

(Cl. D56—4)

To all whom it may concern:

Be it known that I, Charles C. Walker, a citizen of the United States, residing at Winfield, in the county of Henry and State of Iowa, have invented a new, original, and ornamental Design for Dust Cover for Voice Recording Machines, of which the following is a specification, reference being had to the accompanying drawing, forming part thereof.

Figure 1 is a perspective view of the dust cover of my design viewed from one side thereof; Fig. 2 is a perspective view of the dust cover of

my invention viewed from a position beneath the cover; Fig. 3 is a longitudinal sectional view of the dust cover of my invention taken on line 3—3 of Fig. 4; and Fig. 4 is a transverse sectional view of the dust cover of my invention taken substantially on line 4—4 of Fig. 1, showing my new design.

I claim:

The ornamental design for a dust cover for voice recording machines, as shown.

CHARLES C. WALKER.
